UNITED STATES PATENT OFFICE.

JOHN MCLEAN, OF BROOKLYN, NEW YORK.

DESIGN FOR A SETTEE.

SPECIFICATION forming part of Design No. 23,472, dated July 17, 1894.

Application filed June 16, 1894. Serial No. 514,807. Term of patent 7 years.

To all whom it may concern:

Be it known that I, JOHN MCLEAN, a citizen of the United States, residing in the city of Brooklyn, Kings county, and State of New York, have invented and produced a new and original Design for Settees, of which the following is a specification.

The leading feature of my design consists in a settee having ornamental arms and an ornamental back of essentially the configuration and representation exhibited in the accompanying drawing forming part hereof, which shows a view in perspective of a settee embodying my design.

15 In the drawing A is the seat of the settee bordered by an ornamental apron *a*.

B B are the legs of the settee, and *b b* are ornamental scrolls between the legs *B B*.

C is the back of the settee consisting of the ornamental scrolls *c c'* and the surmounting 20 top ornaments *c'*.

D D are the ornamental scroll-work arms of the settee.

What I claim is—

The design for a settee, substantially as 25 shown and described.

JOHN MCLEAN.
